HAIR THINNING DEVICE

Morris Udkovich, Detroit, Mich., assignor, by
mesne assignments, of one-half to Mary K.
Ziganek, Detroit, Mich.

Application September 1, 1934, Serial No. 742,452

12 Claims. (Cl. 30—1)

This invention relates to improvements in barbers' implements and pertains particularly to an improved hair thinning device.

The primary object of the present invention is to provide an improved hair thinning device by means of which the hair may be accurately and safely thinned and without requiring the services of an expert in the work.

Another object of the invention is to provide a hair thinning device having a comb combined therewith and operating on the principle of a pair of scissors.

Still another object of the invention is to provide a hair thinning device which is so designed that only a very small portion of the hair taken up by the comb unit will be cut away.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view in side elevation of the device embodying the present invention.

Figure 2 is a longitudinal section through the body portion of the device, one blade of the holding spring being grooved.

Figure 3 is a sectional view taken on the line 3—3 of Figure 2.

Figure 4 is a sectional view taken on the line 4—4 of Figure 2.

Figure 5 is a view in side elevation of a portion of a modified form of the invention.

Figure 6 is a view showing one side of the shell of the modified form removed, a portion of one of the cutters being broken away.

Figure 7 is a sectional view taken on the line 7—7 of Figure 6.

Figure 8 is a sectional view taken on the line 8—8 of Figure 6.

Referring to the drawings wherein like numerals of reference designate corresponding parts throughout the several views, the numeral 1 indicates the body of the device which is in the form of an elongated flat shell which tapers off at one end to the point 2, while the other end is cut square across and is open. Along one edge of the shell are formed the spaced parallel teeth 3, and the edge wall of the shell between these

teeth is cut away to form the crotches 4 which extend through the wall of the shell and to a depth below the same substantially equal to the thickness of the wall.

Secured in the open end of the shell 1 against one side wall thereof is the shank portion 5 of a handle 6. This shank has extending therethrough and through the opposite walls of the shell, the pivot screw 7 which has its head countersunk in one side wall of the shell, as illustrated in Figure 1.

Disposed against the opposite side wall of the shell 1 from the handle shank 5 is a disk 8 which is attached to the shank 9 of a movable handle 10. This disk has the pivot screw 7 extending centrally therethrough and oscillates on this screw shank when the handle is moved relative to the fixed handle 6. An ear 11 forms an edge extension of the disk 8 and is provided with a suitable aperture for the reception of a pivot pin 12.

Disposed in the shell are two cutter blades, each of which is indicated by the numeral 13. Each of these blades has formed along one edge the series of teeth 14, one side of each of which is straight and extends perpendicularly to the blade, while the other side curves inwardly to join the inner end of the straight side of the next adjacent tooth. As illustrated, the cutter blades are disposed in side by side relation within the shell 1 so that the curved edge of each tooth of one blade is disposed beside the straight edge of a tooth of the other blade. Thus, when the blades are reciprocated so that they move in opposite directions in the shell, the curved edges of the teeth of one blade will move toward and away from the curved edges of the other blade. As illustrated, the height of the blades 13 is equal to the interior width of the shell so that the teeth of the blades will move across the notches formed beneath the inner surface of the edge wall through which they are cut.

Each of the blades 13 has a slot 15 cut obliquely therein in the end nearest the ear 11 and the oblique slot of one blade is disposed to extend across the oblique slot of the other blade and the pin 12 which is carried by the ear 11 is arranged to slide in these slots. Thus, when the disk 8 is oscillated so as to swing the ear 11 and pin 12 back and forth in an arc across the shell 1, the pin will engage the walls of the slots 13 and cause one blade to move forwardly in the shell and the other to move rearwardly so that the teeth of the blades will alternately meet at the centers of the crotches 4 and separate.

Each of the blades 13 has an aperture 16 formed adjacent its transverse center and disposed between each blade 13 and the adjacent side wall of the shell 1 is a bowed flat spring 17 which has an outstruck portion or button 18 which positions in the adjacent aperture 16, the ends of the flat bowed spring slidably pressing against the adjacent wall of the shell.

In Figures 5 to 8 inclusive is shown another form of the present invention. In this form, the body portion, which is indicated generally by the numeral 19, is of the same configuration as the body 1, being relatively broad, flat and hollow, except that at the open end, a cuff-like extension 20, is formed. This body 19, which constitutes a shell housing for the cutters, is divided on a plane passing between its broad side faces to form the two halves 21 and 22. The teeth 23 are formed integral with one half only of the shell, as illustrated in Figure 7. However, the crotches 24 between and at the bases of the teeth extend below the top edge of the adjacent shell half 22, and the top edge of this other half also is provided with crotches, as indicated at 25, to match those in the portion 21.

Disposed within the body are the two cutter bars 26 and 27. These bars are of the same construction as the bars 13 insofar as the formation of the teeth 28 is concerned. However, the bar 26 is fixed against movement, having apertures for the reception of the fixed interiorly threaded hollow studs 29 which, as shown in Figure 7, are secured at one end to the wall of the half 21 of the body shell. These hollow studs act as spacing elements between the two portions 21 and 22 of the shell and when the portion 22 of the shell is in place against the portion 21, screws 30 are extended through apertures in the shell portion 22 and into the hollow studs in the manner shown. The cutter bar 27 has the pair of short longitudinally extending slots 31, therein, through which the studs 29 pass, and this cutter bar is slideable on the studs relative to the bar 26. The cutter bar 27 extends at its rear end beyond the rear end of the fixed bar 26 and this extended end is provided with the oblique slot 32 for the purpose about to be described.

Extending transversely through the two portions of the cuff-like end 20 of the body shell is a pivot screw 33, the head of which bears upon one side of the shell while the threaded opposite end threadably engages in an aperture in the other side of the shell, and this pivot screw is surrounded by a bushing or spacing collar 34, which acts to prevent the two sides of the shell being drawn too tightly together so as to bind the handles 35 and 36 to the point where the operation of the device would be difficult. The handles 35 and 36 are provided with the usual finger openings like those shown in Figure 1, and the handle 36 has an enlarged inner end 37 through which the bushing 34 passes, the handle 35 being provided with a similar enlargement and with the forwardly extending finger 38, which carries a pin 39 which is slidably engaged in the slot 32 of the movable blade. The enlarged portion 37 of the handle 36 is formed to provide a knuckle 40 which bears against the adjacent end of the movable blade while the finger 38 of the other handle passes forwardly along the side of the same toward the end of the fixed blade.

From the foregoing, it will be readily apparent that in the operation of the cutter as illustrated in Figures 1 to 4 inclusive, the two blades are

moved alternately back and forth in the shell, whereas in the form of the invention illustrated in Figures 5 to 8 inclusive, the moving together and apart of the handles 35 and 36 affects only the blade 27. The closing or moving together of the handles causes the knuckle 40 to bear against the end of the blade 27 and the pin 39 to ride upwardly in the rearwardly inclined slot 32, thus forming two points of pressure or fulcrums for forcing the blade forwardly. Upon the separation of the handles, the pin 29 operates alone to retract the movable blade.

In order to make easier the operation of the device as illustrated in Figure 6, the forward end of the housing or shell 19 encloses a spring element 41 which, as illustrated, bears at one end against the adjacent end of the shiftable blade 27 and normally tends to urge the blade in the direction of the handles.

It will be apparent from the foregoing description that when a quantity of hair is picked up by the comb teeth and the oscillatable handles are operated, the blades will be moved one relative to the other in the shell and only those few hairs which are disposed in the crotches between the comb teeth will be cut off. Of course, this operation can be made continuous or intermittent, as desired.

What is claimed is:—

1. A hair thinning device, comprising an elongated flat blade-like body having a plurality of crotches formed across one edge, said body being hollow and said crotches extending through the wall to the interior of the body, a blade disposed within the body and having a plurality of teeth 35 along the edge adjacent the crotches, said blade being longitudinally shiftable in the body to move the teeth transversely of the crotches, rigid teeth projecting from the body from the areas thereof lying between said crotches and means for effecting the reciprocation of the blade in the body.

2. A hair thinning device, comprising an elongated flat hollow body closed at one end and having a plurality of notches cut transversely of one edge and extending through the wall to the interior of the body, a pair of flat blades disposed in side by side relation within the body, a plurality of teeth formed along the edge of each blade which is adjacent the crotches, the blades 50 being relatively movable longitudinally of the body to bring the teeth of one into cutting relation with the teeth of the other at the central parts of the crotches, and means carried by the hollow body at the other end and connected with the blades for causing relative reciprocatory movement of the blades.

3. A hair thinning device, comprising an elongated flat hollow body closed at one end and having a plurality of notches cut transversely of one edge and extending through the wall to the interior of the body, a pair of flat blades disposed in side by side relation within the body, a plurality of teeth formed along the edge of each blade which is adjacent the notches, the blades 85 being relatively movable longitudinally of the body to bring the teeth of one into cutting relation with the teeth of the other at the central parts of the crotches, means carried by the hollow body at the other end and connected with the blades for causing relative reciprocatory movement of the blades, and resilient means interposed between each blade and the adjacent side of the body in which it is housed for maintaining the blades in contacting relation.

4. A hair thinning device, comprising an elongated flat hollow body which is closed at one end and open at the other end, a plurality of teeth extending in spaced parallel relation from one edge of the body and having crotches therebetween which extend through the wall of the body to the interior, a pair of flat blades disposed in side by side relation within the body, a plurality of teeth formed along that edge of each blade which is adjacent said crotches, a handle fixed at the open end of the hollow body, a second handle pivotally attached to and extending into the open end of the hollow body, and means connecting the portion of the pivotally attached handle which is within the hollow body with said blades for effecting the relative reciprocatory movement of the blades. 5
5. A hair thinning device, comprising an elongated flat hollow body which is closed at one end and open at the other end, a plurality of teeth extending in spaced parallel relation from one edge of the body and having crotches therebetween which extend through the wall of the body to the interior, a pair of flat blades disposed in side by side relation within the body, a plurality of teeth formed along that edge of each blade which is adjacent said crotches, a handle fixed at the open end of the hollow body, a second handle pivotally attached to and extending into the open end of the hollow body, means operatively coupling said second handle with the blades to effect relative reciprocation thereof, and resilient elements disposed between the blades and the adjacent sides of the enclosing body for maintaining the blades in contacting relation. 10
6. A hair thinning device, comprising an elongated flat hollow body which is closed at one end and open at the other end, a plurality of teeth extending in spaced parallel relation from one edge of the body and having crotches therebetween which extend through the wall of the body to the interior, a pair of flat blades disposed in side by side relation within the body, a plurality of teeth formed along that edge of each blade which is adjacent said crotches, a handle fixed at the open end of the hollow body, a second handle pivotally attached to and extending into the open end of the hollow body, each of said blades having an oblique slot therein at the end adjacent the pivoted portion of the second handle, said slots being arranged in crossed relation, and a pin carried by the pivoted end of the second handle and engaging in said slots whereby to effect the relative reciprocatory movement of the blades upon its movement transversely of the body by the actuation of the second handle. 15
7. In a hair thinning device, a comb-like body having a hollow back portion and teeth formed along and projecting laterally from one side edge thereof, a pair of toothed cutting elements disposed in the hollow body, said body having crotches extending through the wall thereof between and at the bases of the teeth, the teeth of said cutting element extending above the narrowest portions of said crotches, and means for effecting the movement of a cutting element relative to the other for severing hair disposed in said crotches. 20
8. A hair thinning device, comprising an elongated flat hollow shell divided on planes paralleling the flat sides thereof to form two sections, teeth formed integrally with one section along an edge and projecting laterally thereof, a cutter blade fixed within the shell and having teeth directed toward said first teeth, said shell having crotches cut therein between the first teeth and inwardly beyond the ends of said cutter blade teeth, a second cutter blade having teeth disposed adjacent the first cutter blade teeth, said second cutter blade being longitudinally shiftable, a handle comprising two arms one having an end disposed in one end of the shell and pivotally joined thereto, a finger extending inwardly from the pivoted one of said cutter arms, and a pin carried by said finger and extending laterally into a slot formed in and obliquely of the movable cutter. 25
9. A hair thinning device, comprising an elongated flat hollow shell divided on planes paralleling the flat sides thereof to form two sections, teeth formed integrally with one section along an edge and projecting laterally thereof, a cutter blade fixed within the shell and having teeth directed toward said first teeth, said shell having crotches cut therein between the first teeth and inwardly beyond the ends of said cutter blade teeth, a second cutter blade having teeth disposed adjacent the first cutter blade teeth, said second cutter blade being longitudinally shiftable, a handle comprising two arms each having an end disposed in one end of the shell and pivotally joined thereto, a finger forming an extension of one of the arms within the shell and disposed at one side of the movable cutter, said movable cutter having a slot cut obliquely therethrough, a pin carried by said finger and slidably engaging in said slot, and a knuckle formed at the inner end of the other arm and slidably engaging against the end of the movable cutter. 30
10. An implement of the character described, comprising a comb-like body having teeth and a back, the back of said body being hollow and the spaces between the teeth being extended into the interior of the back, a pair of movable blades in side by side relation in said back, teeth carried by the blades disposed to move across the extended portions of said spaces, and means for relatively reciprocating the blades to effect the cutting by the teeth of hair lying in said spaces. 35
11. An implement of the character described, comprising a comb-like body having teeth and a back, the back of said body being hollow and the spaces between the teeth being extended into the interior of the back, a pair of movable blades in side by side relation in said back, teeth carried by the blades disposed to move across the extended portions of said spaces, means for relatively reciprocating the blades to effect the cutting by the teeth of hair lying in said spaces, and resilient means constantly maintaining the blades with the teeth thereof in close operative relation. 40
12. An implement of the character described, comprising a comb-like body having teeth and a back, the back of said body being hollow and the spaces between the teeth being extended into the interior of the back, a pair of movable blades in side by side relation in said back, teeth carried by the blades disposed to move across the extended portions of said spaces, a pair of scissors-like handles attached to and extending from one end of said body, one of the handles being pivotally mounted, and means operated by the pivotally mounted handle for effecting relative movement between the blades. 45
